UNITED STATES PATENT OFFICE.

ADINO F. FILES, OF MAUMEE, OHIO.

DISPENSING MACHINE.

Application filed February 12, 1927. Serial No. 167,817.

My invention has for its object to provide an efficient means for dispensing different quantities of substances of different kinds as may be required. The invention is particularly adapted for dispensing powdered or paste materials at intervals of time. Thus the invention may be used in connection with filling and wrapping machines wherein receptacles of various kinds are filled.

10 The invention particularly has for its object to provide a hopper mechanism having means for maintaining the material that is dispensed by the mechanism in proper condition to obtain a uniform delivery of the material as well as the uniform consistency where a paste material is dispensed, or a uniform compaction where a powdered or finely subdivided material is dispensed.

The invention may be contained in dispensing machines of different forms and which are used for dispensing a great variety of materials. To illustrate a practical application of the invention, I have selected a structure containing the invention for substantially uniformly subdividing a material and which may be used in conjunction with other mechanisms for manipulating packets or boxes or bags according to the character of the material to be dispensed. The structure selected for purposes of illustration is shown in the accompanying drawing and is described herein-after.

Fig. 1 of the drawing is a side view of the dispensing machine selected for the purpose of illustrating a practical embodiment of my invention. Fig. 2 is a view of a section taken on the plane of the line 2—2 indicated in Fig. 1. Fig. 3 illustrates a dispensing plate that reciprocates to receive and discharge different quantities of the material that is to be dispensed. Fig. 4 is a top view of a hopper, a part being shown removed to illustrate a part of the interior of the hopper. Fig. 5 illustrates a view of a section of the spindle that extends through the hopper. Fig. 6 illustrates a side view of a part of the spindle and shows one of the adjustable blades for regulating the movement of the material to the dispensing plate to maintain the material in the proper condition for delivery in uniform amounts. Fig. 7 illustrates an end view of the lower-most vane which definitely controls the amount of the subdivided portions of the material that is delivered from the machine.

In the form of construction shown in the

drawings, a powdered material is selected for purpose of illustration as the material that is to be dispensed, it being understood, however, that a great many materials may be dispensed by the use of the machine shown or by modifications thereof.

The parts of the machine are supported on a frame 1. A hopper 2 is located on the frame 1 and is provided with a spindle 3 that extends from the top to the bottom of the hopper. The spindle 3 is rotatably supported in a bar 4 that is secured to the upper edge of the hopper. The spindle 3 is rotated by a suitable mechanism such as the bevel gears 5 that are driven by means of a sprocket 6, a sprocket chain 7 and a sprocket wheel 8. A plurality of blades or vanes 10 are secured to the spindle 3. The vanes 10 are curved in form preferably slightly twisted like the vanes of a propeller wheel and also extending at an angle other than 90 degrees from the spindle 3. If desired the edges of the vanes 10 may be curved. Each vane is provided with an enlarged end as at 11, having a threaded opening for receiving a screw. The spindle 3 may have plane surfaces, that is, it may be square in its cross section and be provided with openings through which bolts may be inserted and threaded into the openings in the enlarged ends 11 of the vanes. Thus the screws 12 may be passed through the openings 13 formed in the spindle 3 and threaded into the ends 11 of the vanes 10 and secured in position on one of the plane surfaces of the spindle 3. The center lines of the vanes or the cords of the curved edges of the vanes are located at an angle other than 90 degrees to the planes of the surfaces of the spindle against which the ends 11 of the vanes 10 are drawn by the screws 12. Thus the vanes 10 may be located at different angles with respect to the spindle 3 by turning them about the axes of the screws 12 before the screws 12 are finally tightened to secure the vanes in their positions. By this arrangement certain of the vanes may be located so as to merely cause distribution of the material uniformly throughout the hopper at desired depths of the material within the hopper or the planes may be so arranged that the material will be maintained loose at desired depths or the material may be compacted to various degrees. Where fine powder is being dispensed the humidity of the atmosphere will produce varying compactness according to the adhesiveness of the powder. This will cause the

dispensing of different amounts of the powder on days when the atmosphere is humid from that that is dispensed during the days when the atmosphere is dry. Thus by my invention an adjustment of two or three blades will cause a uniform delivery of the material notwithstanding the changes in the atmosphere. Also, by this arrangement materials of different forms may be dispensed 10 and handled by the machine.

In order to deliver the material in substantially exact quantities from the hopper 2 a dispensing plate 15 is reciprocately moved through the lower end of the hopper. The 15 dispensing plate may be located on the bottom of the hopper and reciprocated by any suitable means, such as, the link 16 that may be connected to one end of the plate and to a crank shaft 17. The plate 15 is provided with 20 an opening 18 of the desired shape according to the form in which it is desired to mold the material as it is being dispensed by the machine. The thickness of the plate may also be varied to produce the material in the desired form when it is finally delivered from 25 the machine. Thus the material may be compacted as may be desired in the opening 18 of the plate 15 and in the reciprocatory movements of the plate 15 may be delivered in the 30 particular molded form according to the thickness of the plate and dimensions and shape of the opening 18 and also delivered in desired uniform quantities or portions.

As the plate 15 is reciprocated, that portion 35 of the plate in which the opening is located is brought into close proximity to the lower end of the spindle 3 where the material that enters the opening 18 in the plate is subject to the control or the adjustment of the vanes that 40 are secured to the spindle. In order to produce the desired compaction within the opening, a foot member 19 is secured to the lower end of the spindle 3 by means of one of the screws 12. The foot member 19 is adapted to 45 pass over that portion of the plate 15 that has the opening 18, and is located in close proximity and may be adjusted so as to be located in contact with the plate. The under surface of the foot member 19, when it is desired to 50 compact the material within the opening 18 of the plate, is inclined upwards and towards, with reference to the direction of rotation of the spindle 3, and so as to gather a portion of the material located in the bottom of the 55 hopper and force it into the opening. The amount of compaction that will thus be produced by the material that is forced into the opening will depend upon the angle of inclination of the foot member 19, also the 60 amount of the material that is thus placed within the opening 18 will be dependent upon the angle of inclination of the under surface of the foot member 19. In the reciprocating movements of the plate 15 the opening 18 is 65 located in position so that the foot member

will pass over it and the movements of the parts of the machine are so timed as to cause this movement once or twice over that portion of the plate having the opening 18, usually but one sweep is sufficient to produce the uniform compaction and filling of the opening. The shaft 17, to which the link 16 is connected, is provided with a sprocket wheel 23 which is connected by means of a sprocket chain 24 to a suitable sprocket wheel located on the shaft 25 to which the sprocket wheel 8 is connected. The sprocket chain 24 may be also connected to a sprocket wheel 26. The plate 15 passes through openings located in the side walls of the hopper 2 and the powder or other material is limited thereby between the planes of the upper and lower surfaces of the plate and the plate substantially fits the openings. Thus I have provided means whereby a uniform amount of material may be delivered from the machine notwithstanding variations in the humidity of the temperature where such variation will modify one or more of the physical characteristics of the material.

If the material is to be compacted in tablet form it may be found necessary to forcibly move the material from the opening of the plate. On the other hand, the quick and rapid movements of the reciprocating member may be sufficient to discharge the material. Also, if the material is not sufficiently compacted it may scatter by reason of the same movement of the reciprocated member. The reversal of direction of movement of the reciprocatory plate will cause the material to drop from the plate at a definite point unless the material is compacted too much. Frequently, where a fine powder having some adherent characteristics is to be dispensed, and particularly under certain conditions of moisture or humidity, or when an oil, although in very small portions, constitutes a part of the mixture, I have found it is necessary to provide means for causing the separation of the material within the opening 18 from the plate. In the form of construction shown, the plate 15 is made elastic and at the end of its outward stroke, with reference to the movement of that portion of the plate having the opening 18, the end of the plate 15 engages a finger 21 that is pivotally connected to a part of the supporting frame 1. The end of the finger 21 is turned towards the plate so that the end of the plate engages the part that corresponds to the knuckle of the finger. As the plate continues to move beneath the finger its outer end is bent downward until the end of the plate passes beneath the pivot point of the finger 21 whereupon the outer end of the plate will be suddenly released from the force that causes it to bend and the quick upward movement produced by the outer end of this sudden release causes the material that is located in the opening 18 to be separated from the plate by reason of its inertia.

and the material will drop from the plate. The form of the material will conform to the shape in which it is molded by the opening 18 in the plate provided the compaction is sufficient.

5 The required compaction will, of course, vary according to the adherency of the material. The plate may be provided with an opening 22 into which the finger 21 may slip to suddenly release the plate.

10 I claim:

1. In a dispensing machine for dispensing separated quantities of a substance, a hopper and spindle located in the center of the hopper, a foot member secured to the end of the 15 spindle, means for adjustably locating the sides of the foot member relative to the axes of the spindle, a member having an opening for receiving the material and means for locating the opening below the foot member 20 to receive material compacted in the opening by the foot member.

2. In a dispensing machine for dispensing separated quantities of a substance, a hopper, a spindle extending to the bottom of the hopper, 25 a plurality of blades connected to the spindle, certain of said blades bent for raising the material in the hopper and other of the blades bent for lowering the material in the hopper, a plate having an opening located at the bottom of a hopper and movable through the lower end of the hopper, means for reciprocating the said plate so as to place the part of the plate having the opening 30 alternatively in position on the inside and 35 outside of the hopper.

3. In a dispensing machine for dispensing separated quantities of a substance in containers, a hopper for containing the material, a plate having an opening located at the bottom of the hopper and movable through the 40 hopper, means for reciprocating the plate so as to place the portion of the plate having the opening alternatively within the hopper and

on the outside of the hopper, means for forcing the material into the said opening when 45 the portion containing it is located within the hopper, and means for jarring the material packed in the said opening therefrom when the portion of the plate having the opening is located on the outside of the 50 hopper.

4. In a dispensing machine for dispensing separated quantities of a substance in containers, a hopper for containing the material, a plate having an opening located at the bottom of the hopper and movable through the 55 hopper, means for reciprocating the plate so as to place the portion of the plate having the opening alternatively within the hopper and on the outside of the hopper, means for forcing the material into the said opening when the portion containing it is located within the hopper, the end portion of the plate having a second opening, a member engaged by the 60 end of the plate and for bending the plate 65 until the member enters the second opening to suddenly release the plate.

5. In a dispensing machine for dispensing separated quantities of a substance in containers, a hopper for containing the material, 70 a plate having an opening located at the bottom of the hopper and movable through the hopper, means for reciprocating the plate so as to place the portion of the plate having the 75 opening alternatively within the hopper and on the outside of the hopper, means for forcing the material into the said opening when the portion containing it is located within the hopper, the end portion of the plate having a second opening, 80 a cam member engaged by the end of the plate and for bending the plate until the cam member rolls into the second opening to jar the material from the plate.

In witness whereof I have hereunto signed my name to this specification.
